CLAIM

The ornamental design for a toy guitar, substantially as shown and described.

DESCRIPTION

FIG. 1 is a first perspective view of a toy guitar showing the design.

FIG. 2 is a second perspective view of the toy guitar of FIG. 1.

FIG. 3 is a front view of the toy guitar of FIG. 1.

FIG. 4 is a back view of the toy guitar of FIG. 1.

FIG. 5 is a first side view of the toy guitar of FIG. 1.

FIG. 6 is a second side view of the toy guitar of FIG. 1.

FIG. 7 is a first end view of the toy guitar of FIG. 1; and, FIG. 8 is a second end view of the toy guitar of FIG. 1. The broken line portions of the drawing figures are included to show portions of the toy guitar that are not part of the claimed design.

1 Claim, 5 Drawing Sheets# US D985,677 S
